INCUBATOR HATCHING COMPARTMENT

Filed May 14, 1929

INVENTOR:
WILLIAM FINNEY HILLPOT,
by *John E. Peagles*,
Attorney.

UNITED STATES PATENT OFFICE

WILLIAM FINNEY HILLPOT, OF FRENCHTOWN, NEW JERSEY

INCUBATOR HATCHING COMPARTMENT

Application filed May 14, 1929. Serial No. 382,902.

My invention relates to mechanism of the general character described and claimed in Letters Patent of the United States 1,489,597 granted to me April 8, 1924, and 1,545,425 granted to me July 7, 1925, and 1,732,891 granted to me October 22, 1929, wherein the means for supporting eggs include a vertical series of trays each supported by detachable connection with a plurality of vertically extending endless chain belts; whereby each tray is pivotally supported so that it may be tilted, to and from horizontal position, and inclined in either of two opposite directions to turn the eggs, with the object and effect of preventing the embryos from sticking to the shells; and each tray may be progressed vertically during the incubating period, from the place of introduction of the fresh eggs to the place of discharge of the hatched chicks.

In the form of my invention shown in said Letters Patent; means are provided, in the lower portion of the egg chamber, forming compartments in rigid relation with each other in which may be placed in succession the trays removed from the chains aforesaid; it being advantageous to put the trays in such compartments with covers over them, when the chicks are about to hatch, to prevent the chicks from escaping into said chamber. However, such stationary compartments are extremely difficult to clean and the purpose and effect of my present invention is to provide portable casing means affording tray compartments and adapted to be placed in spaced relation with each other, to hold the trays and their covers in proper spaced relation during the hatching operation, so as to permit thorough ventilation of the compartments with air circulating in said chamber, and to permit the ready removal of all of the compartment casings, to facilitate cleaning them and the floor of said chamber.

As hereinafter described, such compartments may be formed in a series of foraminous tray casings of rectangular configuration, each having tray spacing means projecting inwardly from its opposite side walls to support the trays in vertically spaced relation, and having casing spacing means pro-

jecting outwardly from said side walls to position the casings in laterally spaced relation.

My invention includes the various novel features of construction and arrangement hereinafter more definitely specified.

Fig. I is a plan view of an egg tray casing.

Fig. II is an elevation of the left hand end of said casing.

Fig. III is an elevation of the right hand side of said casing, as indicated in Fig. II.

Fig. IV is a fragmentary vertical sectional view of an incubator of the type above contemplated, with a convenient embodiment of my invention, including a series of such casings, in the lower portion of the egg chamber.

Fig. V is an end elevation of two egg tray casings, of modified construction.

Fig. VI is a fragmentary inverted plan view of said egg tray casing.

Fig. VII is a fragmentary sectional view of the left hand end of the egg tray indicated in Fig. II, and with a similar egg tray inverted over it to form an inclosure for the hatched chicks.

Referring to the form of my invention shown in Figs. I to IV inclusive; I provide a series of egg tray casings 1, of rectangular configuration, each formed of foraminous material, preferably perforated sheet iron or steel galvanized or otherwise coated with corrosion resisting material.

Each of said casings 1 has, projecting inwardly from the opposite side walls 2 and 3 thereof, a series of tray spacing members 4 and 5 which are preferably T-shaped rails which are welded, soldered, or otherwise rigidly connected with said side walls, in the spaced relation best shown in Fig. II. Each of said casings 1 also has, projecting outwardly from said opposite side walls 2 and 3, casing spacing members 7 and 8 which are conveniently outwardly bent portions of metal bands 9 and 10 which are fixed upon the opposite ends of said casing 1 conveniently by welding or soldering them.

I find it convenient to leave in the bottom wall 11 of each of said casings 1 an opening 12 extending from end to end thereof, to

facilitate the removal of broken egg shells, down, and other débris from the casings.

Each of said casings 1 is readily portable, and a series of them may be placed, side by side, in the lower portion of the egg chamber 14; conveniently resting upon the floor 15 of the incubator structure, which latter may include heat insulated walls 16 and 17, the latter being an end wall provided with the door 18, to afford access to the interior of said chamber.

Said incubator structure includes a series of shafts 20 mounted to rotate in suitable bearings conveniently supported by timbers 21. Each of said shafts carries a pair of chain wheels 23 in axially spaced position thereon, and a chain wheel 24, adapted to respectively support endless chain tray supporting belts 26 and a tray tilting belt 27. Said belts are means for upholding vertical series of egg trays 29, each having suspension means 31 and 32, such as hooks, adapted to be engaged in links or other openings in said belts; as specified at length in my co-pending application Serial No. 362,901 filed May 14, 1929, for Letters Patent of the United States.

As described in that application; each of said trays may be formed entirely of metal, its bottom, sides and ends being formed of a single piece of reticulated wire fabric, which is reinforced at its upper edge by a metal frame upon which said suspension hooks are rigidly fastened, conveniently by rivets which extend through base plates of the hooks, and through said fabric and frame.

As above contemplated; trays containing fresh eggs are detachably suspended at the tops of the series of trays, as indicated in Fig. IV and thereafter progressed downwardly, step by step, during the major portion of the period of gestation, say for twenty days. At the end of that time, the trays at the bottom of the series contain eggs which are about to hatch, and those trays may be removed and placed in the compartments formed in said casings 1, as indicated in Fig. IV; each tray having a cover 30 placed thereover, which cover may be a similar, but empty, tray turned upside down. Each tray with its cover thus forms a cage for the hatched chicks, and is supported in such spaced relation as indicated in Figs. II and IV, to permit free circulation of air vertically and laterally with respect to the contents of each tray.

As indicated in Fig. IV; the casings 1 with their spacing means 7 and 8 above described, (if such means are in horizontal alinement), prevent the removal of any such casing except in the order of its succession from left to right, and impose the necessity of replacing them in reverse order, i. e., in succession from right to left. That construction and arrangement is advantageous under circum-

stances where it is desired to prevent indiscriminate removal of such casings 1 with respect to the series in which they have been placed. However, if it is desired to permit each casing to be removed and replaced, indiscriminately, without regard to its position in the series; I find it advantageous to provide the reinforcing bands 9 and 10 with respective bends 33 and 34 which are like the bends 7 and 8 aforesaid except that they do not come in horizontal alinement with each other and, therefore, do not interfere with each other when the casings are moved in and out of the series.

As far as I am aware; it is broadly new to provide an incubator structure with hatching compartments which are portable and thus capable of being readily removed from their normal position to facilitate cleaning them and the floor or other subjacent portion of the incubator. Therefore, I do not desire to limit myself to the precise details of construction and arrangement herein set forth, as it is obvious that various modifications may be made therein without departing from the essential features of my invention, as defined in the appended claims.

I claim:

1. An incubator egg tray casing including a single foraminous metal sheet bent to rectangular configuration with a waste discharge opening between its opposite edges at the bottom of said casing.

2. A casing as in claim 1, having reinforcing bands at opposite ends thereof extending across said bottom opening.

3. In incubator hatching compartments; the combination with a portable foraminous tray casing, of rectangular configuration; of egg tray spacing means projecting inwardly from opposite side walls of said casing; casing spacing means projecting outwardly from said side walls; and reinforcing bands respectively at opposite ends thereof; said casing spacing means being outward bends in said bands.

4. In incubator hatching compartments; the combination with a portable foraminous tray casing, of rectangular configuration; of egg tray spacing means projecting inwardly from opposite side walls of said casing; casing spacing means projecting outwardly from said side walls; and reinforcing bands respectively at opposite ends thereof; said casing spacing means being outward bends in said bands, which extend at different levels at the respectively opposite ends of the casing.

5. In incubator hatching compartments; the combination with a portable foraminous tray casing, of rectangular configuration; of egg tray spacing means projecting inwardly from opposite side walls of said casing; casing spacing means projecting outwardly from said side walls; and reinforcing bands

respectively at opposite ends thereof; said casing spacing means being outwardly extending projections on said bands.

6. A structure as in claim 5; wherein the 5 casing spacing means extend at different levels at respectively opposite ends of the casing.

In testimony whereof, I have hereunto signed my name at Philadelphia, Pennsylvania, this 7th day of May, 1929.

WILLIAM FINNEY HILLPOT.
